UNITED STATES PATENT OFFICE.

EDWARD J. DASCHBACH, OF PITTSBURG, PENNSYLVANIA.

DESIGN FOR A GAS-BURNER.

SPECIFICATION forming part of Design No. 29,839, dated December 20, 1898.

Application filed July 6, 1897. Serial No. 643,662. Term of patent 14 years.

To all whom it may concern:

Be it known that I, EDWARD J. DASCHBACH, of Pittsburg, in the county of Allegheny and State of Pennsylvania, have invented a new and original Design for Gas-Burners, of which the following is a full, clear, and exact description, reference being had to the accompanying drawings, forming part of this specification, in which—

Figure 1 is a front elevation of a gas-burner embodying my design. Fig. 2 is a horizontal section on the line II II of Fig. 1, showing the front plate of the burner.

My design consists in a gas-burner which is curved both transversely and vertically and arranged to set in an upright position.

In the drawings, 2 is the burner-plate,

which is curved both transversely and vertically, and 3 are the perforations therein.

I have shown the burner as provided upon its face with blocks 4, whose faces are of woolly appearance; but the essential feature of my design lies in the curving of the burner transversely and vertically.

I claim—

The design for a gas-burner, substantially as herein shown and described.

In testimony whereof I have hereunto set my hand.

EDWARD J. DASCHBACH.
